Primary Examiner — John R Yeh(57) **CLAIM**

The ornamental design for a water spill management apparatus, as shown and described.

DESCRIPTION

FIG. 1 is a front-top-right perspective view of a water spill management apparatus in a closed configuration, showing my new design;

FIG. 2 is a rear-bottom-left perspective view thereof;

FIG. 3 is a front elevational view of the present invention, showing the plane upon which a cross sectional view is taken as shown in FIG. 4.

FIG. 4 is a longitudinal cross-sectional view taken along line 4-4 in FIG. 3.

FIG. 5 is a front elevation view of the present invention, showing the plane upon which a cross sectional view is taken shown in FIG. 6.

FIG. 6 is an enlarged transversal cross-sectional view taken along line 6-6 in FIG. 5.

FIG. 7 is a rear elevational view thereof;

FIG. 8 is a top plan view thereof;

FIG. 9 is a bottom view thereof;

FIG. 10 is an enlarged right-side elevational view thereof, where the right elevational view is identical thereto; and,

(Continued)

FIG. 11 is a front-top-right perspective view of the water spill management apparatus in an opened configuration.
